GAS BURNER HEAD

Almer H. Brodbeck, St. Louis, and Harold C. Reinhart, Ferguson, Mo., assignors to Food Giant Markets, Inc., a corporation of New Jersey.

Application January 16, 1956, Serial No. 559,455

1 Claim. (Cl. 158—116)

This invention relates to gas burner heads used on cooking ranges.

Among the several objects of the invention may be noted the provision of an improved burner head adapted to burn evenly at all burning rates without flash back through the burner ports and without blowout; the provision of a burner head of the class described in which an optimum of secondary aeration is obtained at all burning rates; and the provision of a burner head of this class provided with means to inhibit clogging due to spill-over from cooking vessel contents, but which if clogged may readily be disassembled for convenient cleaning. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claim.

In the accompanying drawings, in which one of various possible embodiments of the invention is illustrated,

Fig. 1 is a vertical section through a burner assembly made according to the invention;

Fig. 2 is a right-hand elevation of the assembly shown in Fig. 1;

Fig. 3 is a plan view of the assembly, parts being broken away for purposes of description; and,

Fig. 4 is an enlarged fragmentary detail of the upper left-hand portion of Fig. 1.

Corresponding reference characters indicate corresponding parts throughout the several views of the drawings.

Referring now more particularly to the drawings, there is shown at numeral 1 an annular hollow body, one side of which is bulged as shown at 3 so as to provide for attachment of a fuel supply pipe 5. Gas and an appropriate amount of primary air are supplied to the body by the pipe 5. A base 7 of the body 1 is provided with a threaded opening into which is threaded the lower end 9 of a tube 11 which preferably has a small upward flare. The tube extends through an upper opening 13 in the body 1, a substantial annular space being provided between the sleeve and the opening. About the opening 13 is machined a flat seat 15 which is surrounded by a vertical sleeve 17. The seat 15 supports a ring 19 which at its upper end is flanged inward, as indicated at 21. This flange 21 engages an outer bead 23 on the tube 11, so that by telescoping the sleeve 19 and tube 11, concentricity may be obtained readily.

The tube 11 is outwardly flanged above the bead 23, as indicated at 25, the lower side of this flange being made flat for flatwise substantially sealing engagement with the flat top of the flange 21. The threads 27 between the tube 11 and base 7 are machined concentrically with the sides of the sleeve 17, so that upon assembling the parts, concentricity is assured between the outside of the ring 19 and the inside of sleeve 17. This provides for an

2

accurately formed cylindric annular port 29 between the ring and the sleeve.

The ring 19 is provided with a lower tier of ports, for example, twelve No. 51 drill holes 31 equally spaced. 5 The sleeve is also provided with an upper tier of forty vertically disposed slots 33 which are approximately .070 inch wide and .187 inch long. These dimensions are on the basis of an inside diameter of the ring of approximately 2 1/2 inches. The locations of the tiers of openings in the ring 19 are such that the ports 31 lie below the upper margin of the sleeve 17; whereas the slots 33 are positioned above this margin.

A wire screen 35 is snugly telescoped in position in the ring 19 behind the ports, seating upwardly on flange 21. 15 This may be referred to as a Davy screen, inasmuch as it prevents flash back, particularly through the slots 33. It is composed of approximately .018 inch diameter wires woven to approximately 18 mesh.

On the side of the body 1 opposite the bulge 3 is a second bulge 37 of hollow form, slotted on one side as indicated at 39. A portion of this bulge is open at the bottom for the reception of a fuel supply pipe 41. At 43 is shown in dotted lines a constantly lighted pilot-flame device. When fuel and primary air are introduced into the port 37, a vertical fishtail flame is produced from the slot 39, the same being ignited by the flame of pilot 43.

Assuming that fuel, including primary air, is introduced into the body 1 through pipe 5, this will pass into the ring 19 and escape through both the upper slots 33 and lower circular ports 31. Ignition takes place from the flame issuing from slot 39. The screen 35 prevents flash back. 30 Gas escaping from slots 33 provides a ring of spaced flames, secondary aeration of which is very efficient because of the large lateral flame areas presented to secondary air, which is upwardly convected outside of sleeve 17.

Fuel and primary air which escape through the ports 31 into the circular port 29 first spread into a complete ring therein. This fuel and air move upward and have the effect of maintaining a steady burning characteristic for the gas escaping through the slots 33, even at low burning rates through the latter. It will be noted in this connection that a thin cylinder of fuel including primary air rises from the circular port 29 just within the 35 upwardly convecting secondary air around sleeve 17. The lengths of slots 33 are parallel to this upward flow and provide a large amount of free lateral space for effective mixing. While the screen 35 is shown as covering the ports 31, this is optional, it being more important 40 that it shall internally cover the larger slots 33.

The flange 25 overhangs the sleeve 17 so as to act as a protective eave against spill-over from cooking vessels being heated, preventing such spill-over from entering the ports 29, 31, 33. On the other hand, should 45 unusual circumstances cause such material to effect clogging of any of the ports 29, 31, 33, it is a simple matter to unscrew the tube 11 and to disassemble therefrom the ring 19 and screen 35 for cleaning. Reassembly is equally simple, since all that is required is to telescope the assembly of screen 35 and ring 19 on tube 11, engaging the flange 21 around the bead 23. Or, this assembly 35, 19 may be placed on the seat 15. Then the tube 11 is screwed into the base 7 until sandwiching pressure is applied to the ring 19. Coaxial alignment of the parts 11, 19 and 17 is practically automatic. The flange 25 provides a good, large-diameter purchase for gripping the tube 11 in order to loosen or tighten it.

In view of the above, it will be seen that the several objects of the invention are achieved and other advantageous results attained.

As various changes could be made in the above constructions without departing from the scope of the in-

vention, it is intended that all matter contained in the above description or shown in the accompanying drawings shall be interpreted as illustrative and not in a limiting sense.

We claim:

A gas burner head comprising an annular gas-transmitting body having an upper opening and a lower threaded opening, a tube threaded into said lower opening extending with substantial clearance through the upper opening, an outwardly directed flange on the tube above the upper opening, an inward annular seat located around said upper opening, an inwardly uninterrupted cylindric marginal sleeve extending up from said seat part way to said flange, an externally uninterrupted cylindric ring extending between the seat and the flange and spaced a substantial distance outward from the tube and a relatively small distance inward from the sleeve, said ring extending vertically across the space between the upper end of the sleeve and said flange and having a lower tier of openings within the sleeve, which openings are of relatively small individual and total areas, and an upper tier of ports exposed in said space, which ports are of relatively large individual and total areas and being vertically elongate, a circular screen telescoped within said

ring and covering said elongate ports, the space between the sleeve and the ring being characterized by the absence of any transverse obstruction thereacross, whereby there is provided a small continuous ring of flame at the upper end of said sleeve and beneath said elongate ports and positioned within upward flow of secondary air from the outside of the sleeve for unimpeded aeration of gas flowing from the elongate ports, said tube, ring and screen being freely removable from the body by unthreading the tube.
